(57) **CLAIM**

The ornamental design for a screen for rain gutter, as shown and described.

DESCRIPTION

FIG. 1 is a front, top, and right side perspective view of a screen for a rain gutter showing my new design, the broken lines showing the rain gutter being illustrative of environmental structure only and forming no part of the claimed design;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a right side elevational view thereof, the left side being a mirror image and the broken lines showing the rain gutter being illustrative of environmental structure only and forming no part of the claimed design.
